United States Patent Office.

NATHAN F. MATHEWSON, OF BARRINGTON, RHODE ISLAND.

Letters Patent No. 77,634, dated May 5, 1868.

IMPROVEMENT IN MOWING-MACHINES.

The Schedule referred to in these Letters Patent and making part of the same.

TO WHOM IT MAY CONCERN:

Be it known that I, NATHAN F. MATHEWSON, of Barrington, Bristol county, Rhode Island, have invented new and useful Improvements in Mowing-Machines; and I do hereby declare the following to be a full and exact description of the same, reference being had to the drawings that accompany and form a part of these specifications, in which—

Figure 1 is a view of the machine in perspective.

Figure 2, sectional view on-line *a b*, shown in fig. 1.

Figure 3, sectional view cut on the line *c-d*.

Figure 4, transverse section of a portion of that shown in fig. 3.

Figure 5, sectional elevation on a line with the cutter-bar and the axle of the principal driving-wheel.

Figure 6, sectional elevation on a line with the gear-shaft and seat-standard.

Letter A, the platform to which the various other parts are attached, in manner shown in the various figures of the drawings.

Letter B, principal driving-wheel placed on the left side of the machine, and on a line with the cutter-bar.

Letter C, another wheel placed in the rear of the cutter-bar, as may be seen in fig. 1. This may also be used as an auxiliary driving-wheel.

Letter D, driving-shaft, with small gear-wheels in each end, through which it is made to rotate by the gears on the wheels B and C, one or both.

Letters E E, small gears, loose on the shaft D, and actuated by the gear of the driving-wheels.

Letter F, bevel-gear wheel on the driving-shaft D, and located as represented in fig. 2.

Letter g, a short shaft, hung transversely to the shaft D, and has on one end the small gear h, which meshes into the gear-wheel F. On the other end it has the crank-wheel i.

Letter J, a firm rod, which attaches to the wheel i, and to the inner end of the cutter-plate, and propels the latter.

Letter K, a double bar or frame, in the form of the letter X, with hinges at the four extremities. To the two lower ones the cutter-bar is attached, as shown in fig. 1; the other two are attached to the platform.

Letter M, a shoe on the inner end of the cutter-bar.

Letter N, a curved elongation of the shoe m.

Letter O, a strap of iron formed somewhat in the form of the letter V, and attached to the platform, as shown in fig. 1. This strap o acts as a support to the cutter-bar, in connection with the elongation of the shoe m, the said elongation having its upper end turned around the larger standard of the strap o.

Letter P, a double wedge-key, with its upper and lower ends fitted to pass through slots in the straps r r, and its central portion fashioned so as to form one-half of the journal-box for the pin q.

Letter S, bolt by which the ends of r r may be brought nearer together. This will force the bevelled-key parts of P further through the slots in the straps r r, carrying the whole of P towards the pin q, and thus taking up the wear at this point.

Letters u u, chucks on the shaft D, and connected with the wheels E E.

Letters v v, pins or stops on the shaft D, to receive the shoulder of the wheels E E.

Letters w w, rods leading from the cam-wheels x to the chucks u.

Letters y y, gauges or stops to the wheels x.

Letters z z, rods leading from the wheels x up through the platform A, to within easy reach of the driver on his seat.

Letter a, driver's seat.

Letter b, springs to support the seat.

Letter c, tubular post or standard.

Letter d, counterpart to c, with threads, (see fig. 6.)

- 1, ratchet-wheel, by which the cutter-bar is raised or lowered.
  - 2, lever for operating the ratchet-wheel.
  - 3, spring-pawl.
  - 4, wedge or cam for relieving the pawl.
  - 5, pedal by which the pawl is operated.
  - 6, spring-strap below the platform, to which are attached the lower end of the pedal 5, and also the lower end of the wedge 4.
  - 7, chain connecting the cutter-bar with the wheel 1.
  - 8, a foot-board or dasher. Immediately in the rear of this is a cover, opening into a tool-box.
  - 9, a small portion of the platform A raised on hinges, giving convenient access to the parts below for oiling.
- Having, as I think, sufficiently described the various parts that relate to my invention, I will give some explanation of the manner of working.
- Fig. 1 shows the machine ready for the grass, only the cutter-bar requires to drop lower to cut the grass close. To do this the operator puts his foot to the pedal, which, on being depressed, carries down the spring 6, which in its turn depresses the wedge or cam 4, which, by carrying back the pawl 3, relieves the ratchet-wheel 1, and the cutter-bar falls to the position required.

It may be remarked here that the frame *k* is made of wide strap-iron, and so formed as to slide readily over stones or other obstructions, and also affords complete protection to the driving-rod *J*.

To connect the gear *E* on the driving-shaft *D* so as to make the cutter-bar vibrate, the operator puts his hand to rod *z*, on the left of the seat, and depresses it, thus actuating the wheel *x*, the rod *w*, and the chuck *u*, which moves the wheels *E* *E*, so as to bring the shoulder thereof in contact with the pin *V*. This provides for rotating the shaft *D*, and its motion being transmitted through the short shaft *y*, to the connecting-rod *J* thereby, throws the cutters in vibration.

This throws the work of driving the cutters entirely on the wheel *B*. There is a purpose in this arrangement, viz, to counteract the side-draught, as it is called, produced by the position of the cutter-bar, necessarily far out to the right of the line of draught. Throwing the wheel *B* some distance, in the opposite direction, that is, to the left, this side pressure, so wearisome to the horses, is almost entirely avoided.

I arrange the wheel *B*, the crank-wheel *i*, the driving-rod *J*, and the frame *k*, all on one and the same vertical plane, which obviates much of the jar and tremulous motion felt in machines now in use.

The other wheel, *C*, being connected with the shaft *D* by the same device as *B*, may be made to assist in driving the cutter-bar.

The screw in the seat-post renders it adjustable as to height, to suit any person, so that they can conveniently operate the rods *z z* and the pedals 5. I do not, however, confine myself to the use of a screw, as a rack and pawl, or other equally effectual device, may be substituted.

My improvements relate principally to the following particulars, viz:

First, method of dropping the cutter-bar.

Second, arranging the cutter-bar on or near a line vertical with a line running through the axle of the wheel *B*.

Third, form and arrangement of the frame *k*, to which the cutter-bar is hung.

Fourth, manner of shipping and unshipping the gear on the shaft *D*.

Fifth, strengthening and supporting the cutter-bar by means of the elongation of the shoe *m* and the use of the strap *o*.

Sixth, taking up or providing for the wear on the journals connected with the driving-rod *J*.

Seventh, providing an adjustable seat.

What I claim as my invention, and desire to secure by Letters Patent, is—

1. The spring-pawl 3, when combined and arranged with the pedal 5, the spring-strap 6, the wedge-key 4, and ratchet-wheel 1, substantially as described and for the purposes specified.
2. The curved elongation of the shoe *m*, in combination with the strap *o*, for the purposes specified.
3. The rods *z z*, when used in connection with the wheel *x*, the rods *W*, the chucks *u*, and the gears *E*, for the purposes specified.
4. The double wedge-key *P*, when performing the double office of journal-box and key.

NATHAN F. MATHEWSON.
